UNITED STATES PATENT OFFICE.

ARTHUR McARTHUR HAMILTON, OF CHESNEE, SOUTH CAROLINA.

METALLIC-REINFORCED PICKER FOR LOOMS.

1,283,747.

Specification of Letters Patent. Patented Nov. 5, 1918.

Application filed August 9, 1917. Serial No. 185,315.

To all whom it may concern:

Be it known that I, ARTHUR M. HAMILTON, a citizen of the United States, residing at Chesnee, in the county of Spartanburg and State of South Carolina, have invented certain new and useful Improvements in Metallic-Reinforced Pickers for Looms, of which the following is a specification.

This invention relates to pickers for looms and particularly to metallic means for reinforcing the same at the striking face which impinges upon the point of a shuttle.

The object of my invention is to provide for effectively reinforcing and strengthening a picker at the face where it receives the most wear by repeated blows upon the nose of a shuttle. This reinforcement is effected by means of a strip or plate of metal bent into U shape and having a central opening at the striking face of the picker and being rigidly secured in place by rivets which pass through the folds and tongue of the picker and through holes in the side portions of the plate which lie between plies of leather forming the picker.

Heretofore it has been proposed to provide a strip of metal formed with recesses or notches at its ends and cut away at its opposite longitudinal edges toward the middle portion, where it was much narrowed or reduced. This strip, not being fastened by rivets was "capable of sufficient longitudinal movement to permit the leather at the back of the picker to stretch under the action of the picker stick".

This strip encircled the eye and passed around the picker stick, except that it did not cover the front of the picker. The object of this device was to give rigidity to the sides of the picker and to protect the picker stick. My object is to reinforce the striking face of the picker and prevent the folds of leather from spreading and breaking out by the oft repeated blows upon the pointed end of the shuttle, and to this end I provide a metal plate of a construction especially adapted to the purpose.

The matter constituting my invention will be defined in the claim.

50 I will now describe the details of construction of my improved picker by reference to the accompanying drawings in which—

Figure 1 represents a side elevation of a picker.

55 Fig. 2 represents a horizontal transverse section on line 2—2, Fig. 1.

Fig. 3 represents a plan view of the blank reinforcing plate.

Fig. 4 represents a side view of the plate bent into U shape. 60

Fig. 5 represents a front face view thereof.

The picker A is constructed of plies or folds of thick leather or raw hide in a known manner, being formed of an inner 65 ply a and an outer ply a', inclosing a tongue b, composed of two layers or folds of leather. This construction provides an eye c for a picker stick. The inner and outer folds of leather and the tongue are provided with holes through which are passed rivets e for securely holding the parts together. 70

In constructing my improved picker I provide a metal plate F shown as a flat 75 blank in Fig. 3. Centrally in this plate is cut out a part of the metal, forming an opening f which will be substantially the width of the front face d of the picker and of a little greater height than width, as 80 shown. This opening provides upper and lower bands g, g', connecting the opposite side portions f' of the plate for giving the desired strength. Rivet holes x, two in each side portion f' are also punched in the flat 85 blank. The plate F is bent into a U shape forming a front containing the opening f and the two sides f" containing the rivet holes x. In making up the picker the U shaped reinforcing plate is inserted between 90 the inner fold a and outer fold a' of leather adjacent to the tongue b, so that the front opening f shall be at the front of the picker, as shown in Fig. 2. The folds of the leather and the U-shaped metal plate having been assembled around the tongue b, rivets e are inserted through the folds, the tongue and holes x in the sides of the plate and secured by clenching in the usual manner, thereby binding and rigidly holding the 95 reinforcing plate in position, so as to prevent any longitudinal or other movement. The reinforcing plate F strengthens the sides and particularly the front d of the picker adjacent to the tongue b and prevents the outer ply a' from breaking out where the picker strikes the end of the shuttle. The durability and life of the picker are thus greatly increased. The provision of opening f in the front of plate F 100 is necessary in order to prevent the end of the shuttle from striking the metal plate.

110

when it has worn an opening or socket in the outer ply a' of the picker leather. The upper and lower bands g, g' hold the sides together and prevent the plies of leather 5 from being spread and broken out by impact upon the pointed end of the shuttle. The operation of riveting the folds compresses and firmly binds the sides of the metallic plate against the inner folds and 10 the tongue so as to prevent spreading and breaking out of the folds due to the blows of the picker upon the end of the shuttle. I have demonstrated by practical tests that the durability and efficiency of this metallic 15 reinforced picker are increased and that its life is four times that of the ordinary picker made of leather without reinforcing means.

Having described my invention, what I claim, and desire to secure by Letters Patent, is—

In a picker for looms, the combination

with the folds of material, of a U-shaped metal plate extending at the sides and front of the tongue and having an opening in the front of the striking face of the picker, said 25 opening being of a width corresponding to the width of the front face of the picker and of a height slightly greater than the width thereof, top and bottom straps connecting the side portions, and rivets passing through 30 the folds of the tongue and the sides of the plate whereby the folds of picker material will be bound together and reinforced and prevented from spreading and breaking out by impact of the picker upon the end of a 35 shuttle.

In testimony whereof I affix my signature in presence of two witnesses.

ARTHUR MCARTHUR HAMILTON.
